UNITED STATES PATENT OFFICE.

NELSON T. CLINE, OF MCKEES ROCKS, PENNSYLVANIA.

NUT-LOCKING DEVICE FOR AIR-COMPRESSORS.

1,133,537.

Specification of Letters Patent. Patented Mar. 30, 1915.

Application filed December 8, 1913. Serial No. 305,300.

To all whom it may concern:

Be it known that I, NELSON T. CLINE, a citizen of the United States, residing at McKees Rocks, in the county of Allegheny and State of Pennsylvania, have invented 5 a certain new and useful Improvement in Nut-Locking Devices for Air-Compressors, of which the following is a specification.

My invention is designed primarily as an 10 attachment to air compressors or pumps and has for its main object the provision of a simple and practical means for preventing the well known spanner nuts, which perform an important function in devices of 15 this character, from working loose once they are properly adjusted, thus keeping the stuffing box packing tight and avoiding leakage from the air and steam cylinders.

Further, my invention involves, in combination with the locking feature, a dirt or 20 dust protector for the piston rod and oil swab, which latter member is positioned intermediate of the two stuffing boxes and surrounding the said piston rod, thereby 25 preventing, or greatly minimizing, foreign matter from entering the stuffing boxes.

A still further advantage residing in my 30 invention is its simplicity in construction and easy application to and removal from its intended operative position.

The accompanying drawings illustrate one 35 embodiment of my invention, wherein resides a detail form of construction susceptible of various modifications that will be within the scope of the appended claims.

Referring then to said drawings Figure 1 40 is a sectional view in elevation showing my device as applied to an air compressor illustrating the two spanner nuts in their locked position together with the intermediate oil swab; Fig. 2 is a cross sectional view of the 45 device in operative position; Fig. 3 is a side elevation of the device, and Fig. 4 is an end elevation showing the handle or gripping portion having resilient means in conjunction therewith.

As heretofore stated in the preamble to 50 this specification my device is designed for removable position intermediate of the air and steam cylinders of any suitable form of 55 air compressor or pump, but principally those employed on locomotives supplying air to the train line. In practically all of such air compressors there is employed, as a part of the essential equipment, at least two stuffing boxes, in conjunction with each

of which there is utilized a peripherally grooved or fluted nut, commonly known as a spanner nut, in order to hold the required packing within each stuffing box and in close engagement with the reciprocally operated piston rod. Surrounding said rod there is usually employed an adequate oil retaining swab, utilized for a well known purpose.

The detail construction of my invention 60 involves the gripping or handle portions 1 and 2 respectively, which are here shown as being hingedly connected to each other by bolts 3, suitable nuts 4 being employed for a well known purpose. Seated around, or 65 otherwise secured to the said bolts 3 are spring members 5, their outer free ends being housed in and exerting pressure against the two segments of the handle portion. Integral with the said handle portions are 70 semi-circular straps 6, preferably connected by vertically disposed strengthening ribs 7, and rigidly secured to these said members 6 are the sleeve portions 8, the outer free ends of which are designed to abut each other and 75 taken together form a complete circle and adequate protection or dust guard around the oil swab 9 and piston rod 16 when the device is in operative position.

The locking feature of my device designed 80 and intended as a means to prevent the spanner nuts 10 from working loose, involves the longitudinally disposed inwardly projecting ribs 11 carried by the adjustable sleeve segments, said ribs being designed to 85 engage in the registering flutes or longitudinally disposed grooves 12 formed in the peripheral surface of the said spanner nuts. Also carried by the said sleeve segments, and positioned at either side of the said ribs 90 11, are one or more stops or pins 13, which engage against the circumferential shoulder 95 14 of the lowermost nut at either side of the flutes 12, serving as a means for holding the entire device in suspended position, and 100 preventing it from dropping below its intended functional position.

These said stops or pins 13 are likewise capable of abutting the circumferential shoulder of the oppositely disposed nut, 105 thereby arresting longitudinal movement of the sleeve in either direction, when in its locked position surrounding both spanner nuts.

In order to apply my device in operative 110 position the two normally distended portions of the handle are drawn inward to-

ward each other, which action compresses the spring members 5 and separates the abutting free ends of the sleeve segments sufficient to permit free introduction of the 5 spanner nuts, then by simply releasing pressure on said handles the spring elements will automatically force the said handle portions outward and close the gap between the free ends of the sleeve segments, in 10 which position the device will approximately inclose the two spanner nuts and oil swab. It being presumed that the said spanner nuts have previously been properly adjusted and that the vertically disposed 15 flutes of both nuts will be in longitudinal alinement, one with the other, the entire device is manipulated by the operator in order that the ribs 11 will enter and seat in the flutes 12 of both nuts, thereby arresting 20 further rotary movement of the said spanner nuts. At the same time the stops or pins 13 will shoulder against the bottom nut and hold said device in suspension.

Owing to the fact that the two spanner 25 nuts are threadably adjusted in opposite directions longitudinally, they will both be held rigidly in position when locked together, as shown and described, as neither can turn independently without exerting a 30 tightening up function of the opposite nut.

To remove the device from its operative 35 position simply requires compression of the two portions of the handle sufficient to insure clearance of the free ends of said sleeve segments past the spanner nuts. It will therefore be readily apparent that quick application and removal of my device is possible, and when once properly positioned 40 it will perform its several intended functions without further attention. The two semi-circular portions of the sleeve insures an approximate complete barrier or protection around the oil swab and piston rod, in addition to its primarily designed function 45 as a means for locking the two spanner nuts against movement. I have also provided suitable apertures 15 through the walls of said sleeve segments as a means for introducing oil to the said swab. This feature 50 can be eliminated if found unnecessary but is here shown and anticipated as a useful expedient in conjunction with the other more important features.

What I claim as my invention is:

55 1. A locking device for a peripherally grooved nut comprising a pair of spring controlled semi-cylindrical members normally maintained in position to completely encompass the nut, and longitudinally extending means integral with the inner face of said members and engaging in the grooves of the nut for maintaining said members in locking engagement with the nut, one end of the device lockingly engaging the nut and the other end being locked against rotation.

2. A locking device for a peripherally grooved nut comprising a pair of spring controlled semi-cylindrical members normally maintained in position to completely encompass the nut, longitudinally extending means integral with the inner face of said members and engaging in the grooves of the nut for maintaining said members in locking engagement with the nut, said members having additional means carried by the inner faces thereof and capable of engaging the nut to arrest movement in one direction of said members with respect to the nut, one end of the device lockingly engaging the nut and the other end being locked against rotation.

3. The combination with a peripherally grooved nut, of a locking device therefor, said device comprising a pair of semi-cylindrical members capable of completely encompassing the nut and further capable of being removably mounted around the nut, a handle member projecting from one end of one of said members, a second handle member projecting from one end of the other of said members and pivotally connected to the first mentioned handle member, means for maintaining said semi-cylindrical members normally in abutting engagement, and means carried upon the inner face of said members and capable of engaging in the grooves of the nut for locking said members in position with respect to the nut, one end of the device lockingly engaging the nut and the other end being locked against rotation.

4. A locking device for a plurality of alining spanner nuts comprising a pair of spring controlled semi-cylindrical members capable of completely encompassing the nuts, and a plurality of longitudinally extending ribs carried by the inner face of each of said members and capable of engaging in the sides of the nuts for locking said members relatively to the nuts.

5. A locking device for a plurality of alining spanner nuts comprising a pair of spring controlled semi-cylindrical members capable of completely encompassing the nuts, a plurality of longitudinally extending ribs carried by the inner face of each of said members and capable of engaging in the side of the nuts for locking said members relatively to the nuts, and means projecting from the inner face of each of said members and capable of abutting against said nuts for arresting longitudinal movement of said members in either direction with respect to the nuts.

6. A locking device for a plurality of alining spanner nuts comprising a pair of spring controlled semi-cylindrical members capable of completely encompassing the nuts, a plurality of longitudinally extending ribs carried by the inner face of each of

said members and capable of engaging in the side of the nuts for locking said members relatively to the nuts, means projecting from the inner face of each of said members and capable of abutting against said nuts for arresting longitudinal movement of said members in either direction with respect to the nuts, said members being further provided with openings for the passage 10 of oil to the interior of the members.

7. A locking device for a pair of alining spanner nuts comprising a pair of semi-cylindrical members having their inner faces provided with means engaging in the 15 side of the nuts for locking said members

relatively to the nuts, handle members projecting from opposite ends of said semi-cylindrical members, means for pivotally connecting one of said handle members to the other, and resilient means engaging with 20 said handle members for normally acting to maintain the said semi-cylindrical members in the form of a cylindrical body.

In testimony whereof, I affix my signature in the presence of two witnesses.

NELSON T. CLINE.
